[57] CLAIM

The ornamental design for a truss, as shown and described.

DESCRIPTION

FIG. 1 is a front end elevational view of a truss showing my new design;

FIG. 2 is a top plan view thereof;

FIG. 3 is a bottom plan view thereof;

FIG. 4 is a side elevational view thereof, the opposite side being a mirror image;

FIG. 5 is a rear elevational view thereof;

FIG. 6 is an enlarged fragmentary perspective view of the apex portion of the truss; and,

FIG. 7 is an enlarged fragmentary perspective view of the corner section of the truss.

FIG. 5

FIG. 4
